United States Patent Office.

PHILETUS PHILLIPS, OF MATAWAN, NEW JERSEY.

Letters Patent No. 75,572, dated March 17, 1868.

IMPROVEMENT IN MUSICAL NOTATION.

The Schedule referred to in these Letters Patent and making part of the same.

TO ALL WHOM IT MAY CONCERN:

Be it known that I, PHILETUS PHILLIPS, of Matawan, in the county of Monmouth, in the State of New Jersey, have invented a new and useful improvement on a former Improvement in the Art of Musical Notation, which was secured to me by Letters Patent, dated May 27, 1856; and I do hereby declare that the following is a full and exact description thereof, reference being had to the accompanying drawings, and to the figures and letters of reference marked thereon.

The specification and claim in the patent for the former improvement, and which are to be considered as constituting a part of the present specification, are as follows:

"I represent the seven primary notes in music by seven lines, which are used in forming the staff, each of which is different and readily distinguishable from every other. These lines are shown at Figure 1, and are numbered 1 2 3 4 5 6 7. If the syllables, do, re, mi, fa, sol, la, si, be applied to the sounds of the octave, the lowest note, or do, when not occupying a space, is invariably on No. 1; re, for the second note, on No. 2; mi on No. 3, &c., ascending thus through the series in the same order as shown in the figure.

"Five of the said lines, with four intervening spaces, form a staff, for which purpose I take the alternate lines. The notes in the spaces are readily known from the lines above and below. Leger-lines, on the same principle, may be added when necessary.

"If the lowest line of the staff be No. 3, the second will be No. 5, the third No. 7, the fourth No. 2, and the fifth No. 4, which is the natural scale, as shown at Figure 2.

"In the scale of two sharps, as at Figure 3, the lowest line is 2, and the others 4 6 1 3. In Figure 4 (a tune with one flat) the lowest line is 7, then 2 4 6 1.

"No. 1, at the bottom, would be three flats or four sharps; No. 4, at do., two flats; No. 5, at do., three sharps; No. 6, at do., one sharp.

"Thus it may be seen that every possible transposition of the scale may be effected by placing successively each of the several lines for the lowest in forming the staff.

"The advantage claimed for the improvement is this: The position of the notes, both in the natural and transposed scales, is ascertained at a glance, and they are read, without any study or perplexity, by the peculiar character of the line on which each particular note is written.

"What I claim and desire to secure by Letters Patent, is the 'use of a line of a distinct character, on which to write each elementary note, and the transposing of such lines in the manner above described, to effect and denote the different transpositions of the scale.'

Now it has been found that music cannot be printed from movable types when the lines of the staff differ from each other in form and character, without getting up an entirely new font of type expressly for the purpose, and at an enormous expense. Also the setting up of music in such type would require a special apprenticeship, and could never be done with the requisite facility.

These difficulties were not anticipated. Wherefore, to give the invention a practical shape, and yet retain all its advantages, I propose to strike out the lines of the staff, except at their intersections with the bars, (which divide the music into measures,) and to substitute therefor the staff in common use, as shown in Figure 5. Thus the small portions of the lines intersected by the bars will indicate the position of the notes on the staff, as did the whole lines in the former improvement, and all will be equally plain to the eye, and more simple. The bars for the different transpositions are at Figure 6.

The bars may be cast entire, with portions of the lines intersecting, and the types for the bars must be of as many different varieties as there are transpositions of the scale.

What I claim as my invention, and desire to secure by Letters Patent, is—

The combination of the ordinary staff on which music is printed, with bars, (which separate the measures,) intersecting small portions of the staff formed on the principle of the patent of May 27, 1856, as above described.

PHILETUS PHILLIPS.
